UNITED STATES PATENT OFFICE.

LOUIS GRAVEURE, OF NEW YORK, N. Y.

CASING FOR SMOKING PIPES.

Application filed September 21, 1921. Serial No. 502,261.

To all whom it may concern:

Be it known that I, Louis GRAVEURE, a subject of the King of Belgium, and a resident of the city, county, and State of New York, have invented a certain new and useful Improvement in Casings for Smoking Pipes, of which the following is a specification.

This invention relates to an outer ornamental casing for a smoking pipe and the object of this invention is to provide an article of this character particularly adapted for use in connection with corn-cob pipes or other cheaper grades of smoking pipes which are not generally used because of their appearance.

It is well known that the ordinary corn-cob pipe possesses excellent smoking qualities but because of its appearance and cheapness, it is not generally used.

The main object therefore for this invention is to provide an ornamental casing for the bowl of a corn-cob pipe or other cheap grade of pipe possessing good smoking qualities, so that the exterior appearance of the pipe will be greatly enhanced and the existing objections to the use of such a pipe will be obviated.

With these objects and other objects which may hereinafter appear, in view, I have devised a particular arrangement of parts hereinafter set forth and more particularly pointed out in the claims appended hereto.

Reference is to be had to the accompanying drawings, forming a part hereof in which—

Figure 1 is a vertical sectional view of a pipe bowl and casing therefor;

Figure 2 is a front elevation of the casing shown in Figure 1;

Figure 3 is a side elevation of a modified form of casing, and

Figure 4 is a vertical sectional view of the casing disclosed in Figure 3 and the pipe bowl held therein.

Throughout the various views of the drawings similar reference characters designate similar parts.

In the preferred embodiment of my invention as disclosed in the accompanying drawings, 1 indicates the casing, which is adapted to contain a bowl 2 of a corn cob or other pipe. The casing is preferably of cylindrical or tubular nature and may be made of a polished metal perforated with ornamental designs of any desired character, several of

which may be as disclosed in the accompanying drawing.

In the form of my invention as disclosed in Figures 1 and 2, the upper and lower ends of the tubular casing 1 are threaded at 3 and 4 for the reception of the top and bottom plates 5 and 6 of the casing. The bottom plate 6 is shown in the nature of a concavo-convex disk provided with internal threads which are received on the threads 4. The top plate 5 is in the nature of an annular disk adapted to be threaded upon the threads 3. The top plate 5 is provided with a central aperture which lies in alignment with the opening in the pipe bowl and surrounding said aperture is a continuous inwardly extending flange 7 which overlies the upper end of the pipe bowl 2 and retains the same within the casing.

From the side of the casing extends an interiorly threaded and preferably ornamented boss which is adapted to receive a pipe stem 9, said stem being provided at its end with a stud 10 having a threaded portion 11 which threads into the boss 8. The stud 10 projects beyond the casing and into the stem opening 12 in the bowl of the corn cob or other pipe 2 held within the casing.

In Figures 3 and 4 is shown a modified form of pipe casing which is provided with readily detachable top and bottom plates 13 and 14. The top plate is provided with the inwardly extending flange 7, and said top plate 13 and bottom plate 14 are each provided with a number of downwardly extending spring lugs 15 which permit said plates 14 and 15 to snap over the ends of the casing 17, said casing being flared at its ends as at 18, to permit said plates 13 and 14 to snap thereover and be frictionally held thereon.

It will be seen from the foregoing that I have provided a pipe casing from which the pipe bowl contained within the same is readily removable and which provides extremely handsome appearance thus obviating the usual objection taken to corn cob and other cheap pipes. It is obvious that my improved casing may be altered in size and design and that the top and bottom plates may be detachably secured in position in many ways, and various other modifications may be made without departing from the spirit of my invention.

What I claim is:

1. An article of the class described comprising a casing adapted to receive a pipe

bowl, an annular cover detachably secured thereon, a bottom plate detachably secured thereon, a threaded boss on said casing, a pipe stem having a threaded end adapted to extend into said boss and a projecting portion on said stem adapted to project into the pipe bowl held in the casing.

2. An article of the class described comprising a casing for a corn cob pipe consisting of a tubular metal member having a projecting internally-threaded boss extend-

ing from one side thereof, a pipe bowl received within said member with its stem opening in alignment with said boss, means on one end of the member for retaining the pipe bowl within said member, and a stem having a threaded end adapted to be received in said boss and into the stem opening in the pipe bowl.

Signed at the city, county and State of New York, this 3rd day of June, 1921.

LOUIS GRAVEURE.
